Int. Cl. D23—01

U.S. Cl. D23—4

FIG. 1

FIG. 2

FIG. 3

FIG. 1 is a top plan view of an in-line fuel filter showing my new design, the bottom being the same as the top shown;

FIG. 2 is a side elevation view thereof, with a portion of the outer transparent covering broken away for convenience of illustration; and

FIG. 3 is a cross-sectional view taken at line 3—3 in FIG. 1.

The fragmentary broken line showing of a fuel line in FIG. 1 is for purposes of illustration only.

I claim:

An ornamental design for an in-line fuel filter, as shown and described.
